(57) **CLAIM**

The ornamental design for a boat fender support, as shown and described.

DESCRIPTION

FIG. 1 is a front elevational view of the boat fender support of the invention, the opposite side being substantially a mirror image thereof;

FIG. 2 is a left side end view of the boat fender support of FIG. 1, the opposite side being substantially a mirror image thereof;

FIG. 3 is a top view of the boat fender support of FIG. 1; FIG. 4 is a bottom view of the boat fender support of FIG. 1; and,

FIG. 5 is a perspective view of the boat fender support of FIG. 1 shown in use.

The broken line showing of environmental structure in FIG. 5 is for illustrative purposes only and forms no part of the claimed design.
